UNITED STATES PATENT OFFICE.

ELMER E. KLEE, OF TRIPPLETT, MISSOURI.

QUILTING FRAME.

Application filed January 26, 1925. Serial No. 4,891.

To all whom it may concern:

Be it known that I, ELMER E. KLEE, a citizen of the United States, residing at 5 Triplett, in the county of Chariton and State of Missouri, have invented certain new and useful Improvements in a Quilting Frame, of which the following is a specification.

The present invention relates to a ratchet 10 quilting frame or comfort tacking frame, and has for its principal object to provide a knock-down structure so that the same may be stored easily and take up very little room.

A further important object of the invention 15 is to provide a frame of this nature with a detachable leg structure in order that the frame may be supported in a horizontal position when in use or leaned up against a wall or the like when not in use so as to be 20 out of the way.

A further important object of the invention is to provide a ratchet quilting frame which is capable of easy and ready operation from either side.

25 A still further object of the invention is to provide a leg structure for a frame of this nature which may be folded to a contracted position so as to take up little room when not in use.

30 Another very important object of the invention is to provide a quilting frame of this nature with a very simple and efficient structure, one which is fairly reliable in use, inexpensive to manufacture, strong, 35 durable, easy to manipulate, not liable to readily get out of order, readily assembled or disassembled, and otherwise well adapted to the purpose for which it is designed.

With the above and numerous objects in 40 view as will appear as the description proceeds, the invention resides in certain novel features of construction, and in the combination and arrangement of parts as will hereinafter be more fully described and claimed.

45 In the drawing:

Figure 1 is a top plan view of the preferred embodiment of my quilting frame.

Figure 2 is a vertical transverse section 50 through a portion of the frame, taken substantially on the line 2—2 of Figure 3 looking in the direction of the arrow.

Figure 3 is a transverse section taken vertically substantially on the line 3—3 of Figure 1.

55 Figure 4 is a detail perspective of two of the pivoted bracing links, and

Figure 5 is a detail section on an enlarged scale taken substantially on the line 5—5 of Figure 1.

Referring to the drawing it will be seen 60 that suitable rollers are provided on shafts 5 for the reception of the quilt or comfort 6 in the usual and well known manner. These shafts 5 and the side rails 7 form the frame. At both ends of each end of each shaft 5 65 there is provided a ratchet and pawl structure which is indicated in detail in Figure 5. The pawl is indicated by the numeral 8, the ratchet wheel by numeral 9, and the tenon or end of the shaft by numeral 10. 70 Each ratchet wheel 9 is welded or otherwise fixed on a sleeve 11 which extends through the adjacent side rail 7 and a spacing collar 12 is formed on the sleeve between the ratchet wheel 9 and the adjacent rail 7 so 75 as to hold this ratchet wheel in proper position to be engaged by the corresponding pawl 8. A cotter pin 13 is inserted through the sleeve 11 and the tenon 10 so as to lock the former on the latter. These ratchet 80 wheels 9 and their spacing collars and sleeves are interchangeable so that no study is necessary in assembling the device. When these ratchet structures are provided on each shaft it is possible to remove the 85 cotter pin and thus unlock the ratchet wheel from the shaft so that complete operation may be accomplished from the other side of the frame.

The under edges of the side rail 7 are 90 notched as is indicated at 14 for receiving bolts 15 forming part of the leg structure about to be described. The leg structure supporting each side rail 7 is shown to advantage in Figures 2 and 3 and consists of 95 two pairs of legs 16. The legs in each pair converge from their bottoms toward their top ends and receive at their top ends the bolt 15 which holds the legs one on each side of the rail and these bolts are provided with 100 thumb nuts 17 in order that they may be tightened causing the legs to be brought into tight engagement with the side rails. Two brace bolts 18 and 19, one above the other, are provided to hold the legs 16 of 105 each pair in proper spaced relation to each other as shown to advantage in Figure 2. On the upper bolts 19, the links 20 and 21 are pivoted and the link 20 is pivoted at one end to an intermediate point of the link 21 as at 22 and the inner end of the link 21 is provided with an offset hook 23 engage-

able over the upper edge of the link 20. The links 24 and 25 correspond in formation to links 21 and 20 respectively except that they are longer and are attached pivotally to the 5 bolts 18 so that the pairs of legs associated with each side rail converge toward each other upwardly as is shown to advantage in Figures 1 and 3. The links 24 and 25 are provided with transversely extending lugs 10 26 engageable by the notched end of rods 27 pivoted on the bolts 19 thus preventing the pivot point 22 between the rods 25 and 24 from being moved upwardly and of course this also prevents the pivot 22 of rods 21 15 and 20 from being moved upwardly.

It is thought that the operation of the quilting frame will be readily understood without a more detailed description thereof.

When it is desired to store the frame over-night the thumb nuts 17 are loosened and the rails 7 may be lifted from the leg structures and the frame may be leaned against the wall of the room or the like in an out-of-the-way position. The rods 27 may then 20 be swung so as to disengage their notched ends from the lugs 26, the pivot point 22 moved upwardly so as to fold the pairs of legs 16 against each other. It will also be 25 apparent that the device may be just as 30 easily set up again. When the device is to be stored for any great length of time when not in use, the cotter pins 13 may be removed and the side rails 7 may then be removed so that they may be tacked along- 35 side of the rollers and shaft. Thus the whole frame may be stored in a relatively small space. It will further be apparent that this device possesses a very simple, efficient and inexpensive structure which will

attain all the features of advantage enumerated as desirable in the statement of the invention and above description, and that numerous changes in the details of construction, in the material, and in the combination and arrangement of parts may be resorted to without departing from the spirit or scope of the invention as hereinafter claimed or sacrificing any of its advantages.

Having thus described the invention, what I claim as new is:

In a quilting structure of the class described, a frame including a pair of side rails, and a pair of knock-down leg structures for said side rails, each knock-down leg structure including two pairs of legs, the legs of each pair being inclined toward each other upwardly, bolts connecting the upper ends of the legs of each pair, the side rails of the frame adapted to rest on said bolts, a pivot pin piercing the legs of each pair below the bolt thereof, a second pivot pin piercing the legs of each pair below the first mentioned pivot pin, links pivotally engaged with the first pins and pivotally engaged with each other and provided with means preventing the breaking of said links downwardly when in alignment with each other, a second pair of links pivoted on the second pins and pivoted to each other and provided with means to prevent them from being broken downwardly, rods pivoted on the first pins and having notches in their free ends, the second links provided with pins engageable by the notches, to prevent the breaking of the links upwardly.

In testimony whereof I affix my signature.

ELMER E. KLEE.
